UNITED STATES PATENT OFFICE.

GEORGE I. ROCKWOOD, OF WORCESTER, MASSACHUSETTS.

VALVE DEVICE FOR SPRINKLER SYSTEMS.

Application filed October 27, 1919. Serial No. 333,619.

The object of this invention is to provide an improved differential valve device for sprinkler systems which shall be convenient and sure in operation, easy to manufacture, and which also, if desired, can be used to make the system operate interchangeably either on the "dry pipe" plan or the "wet pipe" plan.

In a sprinkler system arranged on the dry pipe plan, compressed air is introduced at a pressure per square inch less than that of the water supply. Two conjointly acting valves are employed, the larger valve being subjected to the air pressure (usually a small amount of water being introduced into the system above the larger valve to seal it against air leaks) and the smaller valve being employed to hold back the water.

As the two valves operate conjointly, the air pressure acting on the larger valve, although less per square inch than the pressure of the water on the water valve, will normally hold the water valve in seated position.

When a dry pipe system is called into operation by the fusing or releasing of one or more of the sprinkler heads, the air will escape through the same and the air pressure in the system will be decreased until the water pressure acting on the water valve will throw both valves to open position and water will flow into the system and out through the released sprinkler heads. When this occurs, an alarm device connected by piping to the space between the two valves is operated.

As air is normally maintained in the sprinkler system, the same is "dry" and therefore is adapted for winter use or for use in locations where the pipes and sprinkler heads are subjected to temperatures below freezing.

Another plan for arranging a sprinkler system is what is called the water or "wet pipe" plan. In this plan the entire system is filled with water under pressure, and a check valve, lifted by the flow of water when one or more of the sprinkler heads is released, is employed to control the flow to the alarm or the alarm actuating device. This plan is used in summer or in a heated building.

When a valve device is used to make the system work on the dry pipe plan, the larger or air valve must not only seat accurately, but, when seated, must act also to hold the

smaller or water valve on its seat. As practice with differential valves has shown, the smaller valve and seat should have co-acting ground metallic surfaces without any play between them.

The larger or air valve, on the other hand, should contact with its seat through a flexible material such as rubber, in order to secure air tightness readily and also to enable the air valve to contact elastically with its seat in advance of putting pressure on the smaller valve.

But there is ordinarily a disadvantage in the use of any known elastic material in a dry pipe valve due to its tendency to cling tightly to its seat by a sort of gluing or corrosive action, the result of the long continued application of the air pressure before the valve operates in a fire. Hitherto such adhesion has been an element of risk of failure of the valve to operate if under low water supply pressure, in the case of those designs of differential valves having—as preferred in the present invention—the axis of the air valve inclined to the axis of the water valve, since such valve devices have air valves of much less area relatively to that of the water valve than when the two axes coincide. Furthermore, as the object of inclining the valve axes to each other is to use a smaller air valve by transmitting part of the thrust of the water valve to the bearing pin or shaft upon which the air valve pivots, it is usually necessary in such valve devices to provide a shaft with a considerable diameter and bearing area, and also a much tighter fit in its bearings than would be necessary in a dry pipe valve of equal size water valve not having its valve axes coincident. This is because in the latter device the air valve bearing shaft has only to support the weight of the valve and guide it to and from its seat, and is not subject to any stress by the pressure of water on the water valve.

In my present invention, I provide means for increasing the leverage of the thrust of the water valve against the air valve, which increase comes into play after movement of the valves has begun, and which multiplies the pressure usually available in valves of this type to pull the rubber off of its seat and to turn the valve about its shaft against the starting friction engendered by corrosion. To accomplish these effects, I have mounted the valves on separate pivots

or shafts and have counterweighted the larger valve so that gravity will act as a force, independent of the water supply, normally to hold said valve on its seat, and will 5 rock said valve away from its seat after a partial movement thereof; and I have provided separable means between the two valves comprising a strut, preferably having a cam combined therewith, loosely pivoted 10 on the water valve and pressed upon by the air valve. I preferably mount this strut on the water valve in such a manner as to allow its angular position to vary slightly as pressure is applied to it by the closing force 15 of the air valve, thus increasing the pressure which holds the small valve to its seat.

The small or water valve may also be counter-weighted to work on the same plan previously described in connection with 20 the large valve and the parts also may be arranged so that the smaller valve when open will act as a lock to keep the large valve from accidentally dropping back to its seat after the valves have been thrown 25 to open position.

When the valve device is used to make the system operate on the wet pipe plan, the air valve is held or left full open in inoperative position and the water valve is set to 30 operate as a check valve to prevent water flowing backing in the system or to the alarm device, except when a sprinkler opens.

As the water valve and seat have to be accurately ground for the reasons previously pointed out, I combine a flexible or yielding valve device with the water valve, which yielding valve controls a port connected to operate the alarm. As this extra 35 valve is yielding or flexible, it will not interfere with the water valve being forced powerfully and accurately to its seat when both valves are used conjointly in the dry pipe plan.

The best way now known to me for practicing this invention is shown in the accompanying two sheets of drawings, in which

Fig. 1 is a sectional elevation of my improved device set to operate on the dry pipe plan;

Fig. 2 is a similar view illustrating the position the valves assume when the system is called into operation;

Fig. 3 is an enlarged view of the separable means between the valves;

Fig. 4 is a plan view of the water valve and associated parts;

Fig. 5 is a view similar to Fig. 1 showing the parts set to operate on the wet pipe plan; and

Fig. 6 is a similar view showing the position the water valve assumes when the system is called into operation.

Referring to the drawings, and in detail—

65 A designates a casing which may be made

out of two shell castings for ease in manufacture and which casing is provided with a removable plate a.

B designates the large or air valve mounted on a plate B' carried or formed on an arm or arms B² swinging or turning on a pivot B³. The arm or arms B² are arranged to form a counter-weight for the large valve B so positioned that gravity will normally act as an independent force to keep the valve 70 B on its seat and so that after the valve is partially lifted or rocked from its seat, gravity will act to rock the valve away 75 from its seat. These parts thus act on the plan disclosed in reissue Letters Patent 80 granted to me October 28, 1919, No. 14,746.

The metal of the arm or arms B² can be employed to get this counter-weighting effect but it is preferred to provide the same additionally with a soft metal plug or core 85 C which can be trimmed or whittled to get exactly the right balancing effect, and the end of the core is projected so as to strike against the metal of the casing to form a stop to limit the full opening movement of 90 the valve B, when the plate a is removed for inspection as indicated in dotted lines in Fig. 1. The arms may also be provided with an additional soft metal stop C' set in position to strike on the removable plate a to 95 determine the open position of the valve B, when the system comes into operation.

The valve B is preferably made of rubber, leather or other flexible material and cooperates with a valve seat or ring D which 100 can be set into the casing. The large valve B and seat D are preferably inclined as shown.

E designates the water valve which cooperates with a ground valve seat F set 105 into the casing. The water valve E is carried by an arm G mounted on a pivot G' on the opposite side of the water way relatively to the pivot B³. The arm G is arranged and shaped so as to counter-weight 110 the water valve E on the same plan that the air valve B is counter-weighted; that is, so that the same will swing by gravity to, the full open position after a partial opening movement thereof, but so that the same will tend normally to seat by gravity. The arm G may be provided with a soft metal core H for this purpose which may be projected so as to form a striking stop for 115 the water valve as it assumes its full open position and which also will act as a closer or valve moving with the water valve for controlling the leak pipe connection as hereinafter described.

The water valve E is held in the arm G 120 by a bolt I threaded into the same as illustrated in detail in Fig. 3. This bolt I has upwardly projected slotted arms I'.

J designates a strut having trunnions J' fitted in the slotted arms I' and loosely held 125

in place therein by caps I^2 attached by screws to the top of the arms I' . A cam J^2 extends from the strut J and engages a leaf spring J^3 having an upward extension J^4 attached by screws to the bolt I , which spring yieldingly holds the strut in upright position. The strut J is thus sidewise yieldingly held in position. The plate B' has a notch B^4 on the under side thereof which 10 engages with the top end of the strut J when the valves are closed. The strut therefore forms a sidewise yielding separable connection between the valves.

By arranging the axis of the strut substantially in line or parallel with the center of the water valve E when the same is closed, the pressure on the air valve is multiplied and transmitted to the water valve with a sort of folding toggle action so that the 20 lighter air pressure is effective to force the water valve more powerfully to its seat than would be the case if the valve B bore directly on the valve E .

This action is obtained because as the air valve is pressed downwardly by the air pressure it will have quite a little swinging movement about its pivot or shaft B^4 . The pressure of this swinging movement will be applied to the top of the strut which will force 30 the water valve to its seat with an increasing leverage or with a folding toggle action, one arm of the toggle being the distance from a notch B^4 to the center B^3 , and the other arm being the distance from the notch B^4 to the center J' .

In the opening operation, the upward pressure of the water on the under side of the water valve will first be applied through the strut with a toggling action to the air valve which will give a very powerful upward thrust thereon to lift the air valve very forcibly from its seat this increasing leverage or toggle action is obtained because as the water valve is pressed upwardly it will 40 turn about its pivot or shaft G' . The pressure of this upward movement will be applied through the trunnions J' . One arm of the toggle will be the radius of the swinging action of the water valve or the distance G' and J' , and the other arm will be the distance J' to B^4 . The continued upward movement of the water valve will tip the air valve over so that it will start on its further swinging movement, the strut J preferably 50 folding back and lying down on top of the water valve as shown in Fig. 6, as the strut J folds down on the nut I , the cam J^2 will snap out of the extension J^4 of the spring J^3 and the strut will remain in its lowered position.

When it is desired to set the strut again into vertical or operative position, the same is forcibly pushed to an upright position, forcing the point of the cam J^2 past the projection J^4 on the spring J^3 . As the lower

part of the cam is made flat where the spring engages the same, the strut will be spring centered or held so that it can have a yielding sidewise movement either way, so that the toggling actions previously described can 70 take place. This folded operation of the strut is advantageous because if the valves should not get to wide open position and should return to their seats after a partial or initial opening movement thereof, the 75 strut J would be out of the way as shown in dotted lines in Fig. 3 so that the water valve would not be held to its seat and water pressure would act on the under side of the large valve and open the same, and prevent what 80 is technically known as "water columning," that is, the filling of the system above the large valve to a sufficient height to keep the valves closed by their differential action, although the system has been called into operation by the release of one or more sprinkler heads.

When the water valve is open if the air valve should for any reason swing back towards its seat, the open water valve will 90 prevent the air valve from returning to its seat, as the plate B' will strike the upper point of the water valve before the valve B can reach its seat D .

To the side of the water valve E is attached a piece of flexible metal K which carries a leather or rubber valve face K' . At the side of the valve seat D , an additional port K^2 is provided to which a pipe extending to the alarm is connected. As this additional valve is flexible or is yieldingly carried by the water valve E , the operation of the seating of the water valve by air pressure acting on the large air valve through 105 the strut or stud J is not interfered with.

A bushing L is threaded into the casing, the inner end of this bushing being machined to form a valve seat and the core H is machined to form a valve to cooperate therewith. A leak or drain pipe L' is connected 110 to the bushing L . When the valves B and E are in closed position as shown in Fig. 1 any slight leakage past the water valve will pass away through the leak pipe L' , but when the system is called into operation and the valves thrown to open position as shown in Fig. 2, this leak or drain will be cut off or closed.

When the device is used on the dry pipe plan, both valves are closed and are set in 120 the position shown in Fig. 1. If the system is called into operation, both valves are thrown to open position as shown in Fig. 2 and an unobstructed flow of water is allowed through the valve device and water will flow to the alarm through the port K^2 .

After operation, when it is desired to reset the valves, the plate a is removed, the large valve swung down to horizontal position as shown in dotted lines in Fig. 1, 130

the water valve pulled down onto its seat, the strut moved back to vertical position, the air valve pushed back onto its seat, and the plate *a* replaced.

5 When the valve device is to be used on the wet pipe plan, the parts are adjusted as shown in Fig. 5, so that the air valve remains open or in inoperative position and the water valve alone is employed. When 10 working on this plan, it is not necessary to drain the space intermediate the two valves and the pipe *L'* is closed by a suitable valve. If the system is called into operation when 15 operating on this plan, the water valve *E* will lift and the valve *K'* will be raised and water will flow through the pipe *K²* to operate the alarm device.

In some uses, it may be desired not to have the water valve balanced so that it will 20 remain in open position after being partially lifted from its seat as for illustration, in places where excessive water hammer may be encountered as in city mains. To provide for this purpose a bolt *M* is 25 threaded into the casing and a collar *M'* is arranged on the end of the bolt. When the screw is withdrawn as far as possible, the same does not interfere with the full 30 opening movement of the counter-weighted water valve as will be seen by referring to Fig. 2. When it is desired to have the water valve always return to its seat, the bolt is screwed into the casing as shown in 35 Fig. 6, which position of the bolt will prevent the water valve from remaining in open position as its center of gravity can not move to the right of its pivot, an ear *G²* being provided on the arm *G* for this purpose. The collar on the bolt will thus 40 determine the adjustment necessary to set the bolt so that the same will not prevent the smaller valve remaining open.

In some cases it may not be necessary to 45 counter-weight the water valve but the construction described is preferred. Some of the combinations herein described and claimed can be employed in a valve device that is only capable of use for one or the other of the two plans described.

50 Many modifications can be made in the detailed arrangements by a skilled mechanic without departing from the scope of my invention as expressed in the claims.

Having thus fully described my invention, what I claim and desire to secure by Letters Patent is:—

55 1. A valve device for sprinkler systems comprising a casing having a large seat, a valve pivoted to the casing, a small valve seat, a smaller valve independently pivoted to the casing, and separable connections carried by said valves and movable relatively thereto and arranged so that when in one position the large valve will act therethrough 60 to hold the smaller valve to its seat, said

valves in their opening movement moving said connections to a position where they remain out of operative relation between the valves, whereby if the large valve returns to its seat after an opening movement thereof said connections will not function to hold closed the smaller valve even if the latter has returned to its seat. 70

2. A valve device for sprinkler systems comprising a casing having a large seat, a valve pivoted to the casing, a smaller valve seat, an independently pivoted smaller valve, a strut pivoted to the smaller valve in position to be engaged by the large valve, a cam extending from said strut, a spring engaging said cam, the parts being arranged so that when an opening movement occurs the strut will be turned down to inoperative position and the cam released from said spring, whereby if the large valve returns to its seat after an opening movement thereof it will not close the smaller valve. 80

3. A valve device for use in sprinkler systems comprising a large valve and seat, a relatively smaller valve and seat and separable means between the valves comprising a pivoted strut carried by one valve and directly engaging with the other valve so as to fold to inoperative position after a 90 partial or initial opening movement of the valves. 95

4. A valve device for use in sprinkler systems comprising a casing having a large and a small valve independently pivoted to the casing, means for counterweighting the small valve so that gravity normally acts to keep the valve on its seat and becomes effective to rock said valve from its seat after a partial movement thereof and to hold the valve in its open position, and separable connections between the valves, the parts being so arranged that after the valves have been opened the small valve will stand in position to prevent the large valve from returning to its seat. 100 110

5. A valve device for use in sprinkler systems comprising a casing having a large valve seat and a small valve seat, valves pivoted to the casing, means for counterweighting the smaller valve so that gravity 115 normally acts to keep the same on its seat and becomes effective to rock said valve from its seat after a partial opening movement thereof, a bolt threaded into the casing and means for determining the adjustment of said bolt so that the same can be set to prevent the smaller valve from remaining open. 120

6. A valve device for use in sprinkler systems, comprising a large valve and seat, a relatively smaller valve and seat, separable means between said valves arranged so that they can be used conjointly or so that the smaller valve can be used alone, a port alongside the smaller valve connected to an 125 130

alarm, and a yielding valve carried by the smaller valve for controlling said port, whereby the alarm will be operated whether the valves are used conjointly or only the 5 smaller valve is used.

7. A valve device for use in sprinkler systems comprising a large valve and seat, a relatively smaller valve and seat, a drain or drip opening for the space between the 10 two valves, and a valve or closure for said opening attached to the smaller valve.

8. A valve device for use in sprinkler systems comprising a large valve and seat, a relatively smaller valve and seat, said valves being set at an angle to each other, a drip 15 or drain opening for the space between the two valves, and a valve or closure for said opening attached to the smaller valve.

In testimony whereof I have hereunto affixed my signature.

GEORGE I. ROCKWOOD.
